LOCK FOR INTERLOCKING FASTENERS

Kurt Robert Jordan, Ludenscheid in Westphalia,
GermanyApplication June 1, 1932, Serial No. 614,724
In Germany January 29, 1932

1 Claim. (Cl. 70—2)

Application has been filed in Germany on the 29th January, 1932, and in Great Britain on the 4th April, 1932.

The present invention relates to sliding clasp fastenings and more particularly to a clasp and locking device for fastenings of this kind.

It is the principal object of the invention to provide means whereby a sliding clasp fastening can be secured in the closed position in such manner as to avoid the possibility of its being opened by unauthorized persons.

With this object primarily in view, according to the invention, a lock or lock member, preferably of the kind used for handbags, is provided at the one end of the slit in the article to be closed by the fastening and a projection or lug which may constitute an eyelet, is provided on the slider serving for opening and closing the fastening or on the manipulating tab thereof, which projection or lug is introduced into and engages with the lock member when the fastening is in the closed position, means, such as a key, being preferably provided for operating the lock member so as to lock the projection or lug in position in the latter.

Some preferred constructional forms of a clasp and locking device according to the invention are illustrated by way of example in the accompanying drawing, in which:

30 Fig. 1 is a side view of one constructional form of a clasp and locking device according to the invention,

Fig. 2 is a plan thereof,

35 Fig. 3 is a side view of a second constructional form according to the invention,

Fig. 4 is a plan corresponding to Fig. 3, and

Fig. 5 is a side view of a third constructional form according to the invention.

40 Referring to the drawing:

The reference letter *o* denotes an article to which a sliding clasp fastening *p* is attached. The sliding clasp fastening *p* serves for closing a slit which is provided in the article *o* and by means of which the interior of the said article, 45 which may, for example, be a handbag, is rendered accessible. A slider *a* is provided which serves in known manner for bringing the interlocking members of the fastening *p* into and out of engagement with one another. At that end 50 of the slit at which the slider *a* is located when the sliding clasp fastening is closed, a lock or lock member *c*, preferably of the kind usually employed for handbags and the like, is fixed

to the article *o*. On the front face of the slider *a* a lock bolt *b* is provided, which, when the slider is brought into the closing position, passes through an opening or slot *d* of the lock *c*. The opening *d* is located directly in the path of motion of the lock bolt *b* so that the latter automatically enters the opening of said lock at the end of the closing movement of said slider and locks the slider in the closed position. The lock bolt *b* may, as is customary in locks of the kind in question, either be provided with a recess or be constructed in the form of an eyelet *m*. The lock *c* retains the projection *b* of the slider *a* in the closed position, prevents undesired movement of the slider *a* in the opening direction. The lock *c* may be operated in known manner by means of a manipulating member or button *i* arranged on the exterior of the lock, thus releasing the lock bolt *b* of the slider *a* so that the slider can be operated for the purpose of opening the fastening. If it is desired to prevent the manipulation of the stud *i* by unauthorized persons, the lock may be locked by means of a key introduced into a key hole *r* provided in the lock *c*. It will be understood that locks or lock members of any desired suitable kind may be employed. If the opening or slot of the lock *c* is located on the face *f* thereof, the lock is arranged so that it is located in the same plane as the sliding clasp fastening (see Figs. 1 and 2), but if the said opening or slot is located on the longitudinal side *e* of the lock the latter will be located perpendicularly to the sliding clasp fastening as shown in the constructional form illustrated in Figs. 3 and 4.

It is to be understood that the internal mechanism of the lock *c* may be of any desired suitable construction and thus does not require further description.

45 I claim:

A locking means for the operating slider of a separable fastener means for the opening in a bag or other receptacle; comprising a lockable member rigidly projecting from said slider in the direction of the closing movement thereof, and a lock mounted at the end of the opening, comprising a casing having an aperture adapted to receive the projecting member, upon the operation of the interlocking fastener by the slider to completely close said opening, whereby said slider may be automatically locked in closing position.

KURT ROBERT JORDAN.
